UNITED STATES PATENT OFFICE.

CLINTON W. WILLIAMS, NOW BY JUDICIAL CHANGE OF NAME JOSEPH CLINTON WILLIAMS, OF LOS ANGELES, CALIFORNIA.

WINDOW BED.

Application filed December 22, 1922. Serial No. 608,489.

To all whom it may concern:

Be it known that I, CLINTON W. WILLIAMS, now by judicial change of name JOSEPH CLINTON WILLIAMS, a citizen of the United States, residing at Los Angeles, in the county of Los Angeles and State of California, have invented new and useful Improvements in Window Beds, of which the following is a specification.

10 This invention relates to bed and furniture forming apparatus, and has for its object to provide a bed structure that is adapted to be readily folded outwardly and inwardly through an ordinary size window

15 so that the bed can be arranged for sleeping use in the open, outside of the wall in which the window is provided.

Another object of the invention is to provide a foldable bed structure which can be extended into serviceable position for adults when arranged exterior to an ordinary size window. Another object is to provide a foldable bed structure which can be compactly folded within a room and disposed 25 either contiguous to a window or otherwise, as for instance when it is desired to use the apparatus as a settee or seat. Also it is an object to provide a foldable bed apparatus which can be arranged when within 30 a room as a bed or cot.

Other objects and advantages will be made manifest in the following specification of an embodiment of the invention illustrated in the accompanying drawings, 35 wherein—

Figure 1 is a perspective showing the bed-frame disposed and unfolded beyond a house, or other building, window.

Fig. 2 is a vertical section through the wall structure showing the connection of the foldable bed-frame to the wall.

Fig. 3 is a detail showing a connecting means for detachably fastening the bed-frame retaining elements to the wall.

Fig. 4 is a perspective showing an end portion of the bed-frame with the end guard in erected position for use when the bed is extended out of the window.

Fig. 5 is a side elevation in detail of a form of hinge joint between foldable sections of the bed-frame.

Fig. 6 is a plan of the pivotal joint of Fig. 5.

Fig. 7 is a detail elevation showing the

fastening of the side guard to an end guard 55 of the bed.

Fig. 8 is a sectional detail of a form of pivotal connection between the bed-frame and its carrying links.

Fig. 9 is a front elevation of the exterior 60 of the side guards of the extended frame.

Fig. 10 is a plan of the extended frame.

Fig. 11 is a vertical section through a wall and showing in end elevation the bed-frame projected through the window and showing 65 in dotted lines the movement of the bed-frame.

Fig. 12 is a side elevation of the interior of the wall and window frame and showing the bed in folded position to form a settee 70 or seat.

Fig. 13 shows in detail the arrangement of the legs of an end guard in frame supporting position.

Fig. 14 is a perspective of the extended 75 and unfolded bed showing a modified form of side and end guards and legs.

Fig. 15 is a perspective of the erected end and side guards of the modified form.

Fig. 16 is an end elevation of the modified 80 form of the bed when erected as a cot supported on the corner legs.

Fig. 17 is a perspective showing the foldable bed window in combination with an awning.

The broad object of my invention is to provide a foldable bed-frame which may be readily projected out through a window when the sections of the frame are folded up and then extended when the bed-frame 90 has been arranged in horizontal position outside of the window, means being provided for foldably supporting the frame to facilitate the inward and outward movement thereof through the window opening.

The apparatus is shown as arranged in combination with a wall W having a window opening O which, for example, may be of ordinary dwelling house dimensions and may, for instance, have a width of two or 100 three feet or three feet six inches, or four feet width, or any other width dimension, these being mentioned as for average sizes of dwelling windows.

The bed, in its illustrated form, consists of a central section 2 of a length not greater than the width of the window opening O so that the frame 2 can be passed in

and out of the window. To obtain a full length bed, there is connected to the frame 2, in any suitable manner, any suitable section or sections adapted to be extended in 5 alinement with the length of the section 2 to provide a full length bed-frame. Therefore, the frame 2 is here shown as having outwardly foldable end sections 3 which are pivotally connected at 4 to the corners of 10 the frame 2. The end sections 3 are adapted to be folded inwardly upon the frame 2 as is shown in Fig. 11 so that the contracted frame can be shifted in and out of the window.

15 To facilitate the movement of the bed-frame and further for the purpose of acting as a substantial support for the same, the inner rail of the bed-frame 2 is shown as pivotally connected at 5 to the contiguous 20 ends of substantial links C, a pair of which are here shown; each link being disposed contiguous to the frame work F of the window. The bed-frame may have a width greater than the opening formed between 25 the sill S of the window opening and the bottom rail R of the window sash, Fig. 12, and to facilitate the movement of the bed-frame through the window opening, the links 6 are shown as pivotally connected at 30 7 to the upper ends of swinging bracket links 8, which are shown as detachably connected to the wall W inside of the window.

It may be desirable to provide for the 35 entire detachment of the foldable bed-frame from the wall structure, and therefore the links 8 are shown as detachably fastened by pivot pins or keys 9 passing, for instance, through an eye device 10 in the form of a screw eye having a screw shank 11 which 40 can be driven into the wall.

When the bed-frame 2 is positioned within the window, as shown in Fig. 12, it may be utilized as a seat or settee and it is then supported upon suitable legs 13 which may 45 have casters 14 enabling the device to be rolled about the floor when it is disconnected from the screw eyes 10 by the removal of the locking pins 9. The legs 13 may form a part of a frame 15 which is 50 adapted to be entirely detached from it end frame 3, which latter is adapted to be folded in under the frame 2. The leg frame 15 may be provided with hooks or other fastening means 16 to engage receivers or 55 slots 17 provided therefor in the end frame 3, it being understood that there is a foot frame for each end frame. Further fastening means may be employed to secure the foot frame 15 in its under-folded position 60 of Figs. 12 and 13, and such fastening means may consist of a simple snap hook or latch 18 which is here shown as being secured to a transverse end member of the frame 2.

65 When it is desired to project the bed-frame out through the window opening O,

the leg frame 15, with the legs, are detached from the end sections 3 and then the main frame 2 is lifted to the dotted line position b, Fig. 11, and passed out through the window; the frame 2 being tilted at a suitable 70 angle so that its upper side will clear the bottom rail R of the window sash. The links 6 are then swung down onto the sill S upon which preferably are placed protecting rails 20 on which the links 6 may slide and rest. When the links are resting on the rails 20 then the frame 2 can be swung to the position a and then continued down to the horizontal position. To provide a desired degree of rigidity and safety after 80 the frame 2 has been turned to its outer horizontal position, it can be fastened up by braces 21.

When the bed-frame 2 has been extended outwardly, the end frames 3 can then be unfolded into alinement with each other and with the bed-frame 2 to form a full length bed apparatus as shown in Fig. 10. Any suitable mattress supporting means as a spring or wire, or other device 22, may be 90 provided upon the sections 2 and 3.

The swinging movement of the bed-frame 2 about its pivots 6 may be facilitated by forming the pivots as of a continuous rod 5^a and supporting on these rods helical springs 95 23, the ends of each of which are so disposed and associated with the contiguous side member of the bed-frame 2 as to tend to swing the bed-frame inwardly; the opposite ends of the springs 23 being shown as 100 associated with the links 6. This provision will, therefore, aid in lifting the frame 2 from the outer extended position to an upright position in the window opening after which the bed-frame can be bodily shifted 105 inwardly by inward movement of the links 6.

The outer side of the extended bed is adapted to be guarded by detachable or foldable outside walls or panels 25, Fig. 9, which may consist of frame sections having lugs 110 or any suitable fastening devices 26 to engage complementary devices or keepers 27, the latter being provided in the outside rail sections of the bed-frame. Preferably the guard panels 25 are of a length to enable 115 them to be folded or nested compactly in the main frame 2 of the bed. The erected guard panels may be connected at their upper meeting corners as by a fastening latch 28.

End guards 30 are provided, and as shown 120 in Fig. 4, each consists of a guard frame which may be rigidly connected to a leg frame 15. Therefore, the leg frames when disconnected from the leg supporting position in Fig. 13 can be applied to the extended ends 3, Fig. 1, so that the guards will extend up as is shown in Fig. 4, in which position they may be latched by central latches 31 provided on the end frames 3. The leg frames may have hooks 32 adjacent to the 125 130

casters 14 of the legs, and these hooks are adapted to enter slots 33 provided therefor in the end frames. It is understood that the method of constructing and mounting the 5 end guards is here shown in one form only as it is obvious that various other end guard and side guard constructions may be employed.

A modified form of the end and side 10 guards and of the supporting legs is shown in Figs. 14 to 16 inclusive wherein the end guards 30 are hingedly connected at 30' along their lower edges to the transverse end 15 bars of the frame and may be swung from an inwardly folded position, Fig. 14, to a perpendicular position, Fig. 15.

A modified form of end legs is shown as comprising substantially triangular or otherwise shaped frames 40 hingedly pivoted at 20 41 to the side members of the unfoldable end frame sections so that the leg frames 40 can be folded inwardly over the inturned end guards 40 or may be extended to perpendicular position as shown in Figs. 15 and 16.

25 The side guard of the modified form consists of a central section 25^a hingedly connected at 25^b so that the side wall on the bed frame 2 is adapted to be swung from a folded to an upstanding position, Fig. 15. The 30 ends of the guard 25^a are provided with foldable wings 25^c shown as hingedly connected at 25^d to the central guard 25^a and they may therefore be folded to an outermost position in alignment with the central section 25^a as 35 is shown in Fig. 15.

The erected guard elements may be suitably secured in upright position as by simple and appropriate latches or fasteners 25^e. It will be seen, therefore, that the modified 40 form of device shown in Figs. 14 to 16 provides guard elements which are permanently but foldably connected to the bed frame. When the bed is to be extended in cot-forming position and supported on a floor, the 45 leg frames 40 are folded down, as is shown in Fig. 16, and the casters 14 thereof will bear upon the floor or other supporting plane.

A feature of my invention is that to 50 secure the maximum degree of safety in the supporting of the foldable bed in the position exterior to the window, means for increasing the stability and support is shown as comprising, in Fig. 17, the combination 55 of the bed with an awning A of any approved and suitable construction. The awning frame is shown as connected to the bed-frame by means of links or suspending devices 50, and if desired the suspending devices 60 may be extended as in the form of chains or other means 51 attached to the primary supports of the awning.

Further embodiments, modifications and 65 changes may be resorted to within the spirit of the invention as here claimed.

What is claimed is:

1. A wall-window bed having a main section of less length than a given window so as to pass fully therethrough in or out, means extensible to form a full length bed 70 outside the wall, and a foldable supporting means attachable to the inner face of the wall and attached to the main section of the bed to hold the bed suspended outside the window and permitting the sash to be substantially closed while the bed is hung outside. 75

2. A bed frame of less length than the width of a given window and having foldable end sections to permit the bed to be 80 passed in folded condition in and out through the window, guard frames adjustable in upright positions on the bed frame and end sections when they are extended, and means attachable to the inner side of a 85 wall and to which the bed structure is hingedly connected so that it may be supported wholly outside of the window.

3. A wall-window bed having a main central section frame of less length than the 90 width of a given window so as to pass fully therethrough in or out, link means pivotally attachable to the inner face of the wall and to which the frame is hingedly attached, and bed sections attached to the ends of the 95 frame so as to be unfolded to make a full length bed frame.

4. A bed-frame of less length than the width of a given window in a wall so as to be wholly folded outwardly and inwardly 100 therethrough, foldable sections connected to the bed-frame and adapted to be extended to form a full length bed, and means for detachably and foldably connecting the bed-frame to the inner face of the wall, the bed 105 having supporting means whereby it can be converted into a bed within the room of which the wall may form a part.

5. A bed structure consisting of a main frame of a width somewhat less than the 110 length of a given window opening in a wall, means for connecting the bed-frame to the wall contiguous to the window in such position that the bed-frame can be wholly passed out and in through the window opening, and foldable sections connected to the bed-frame so that the latter can be formed into a full length bed either inside or outside the wall.

6. A bed structure including links attachable to a primary supporting part, a main 120 bed frame, folding connections between said bed frame and said links whereby, when the structure is secured as to a wall adjacent a window, the bed frame can be bodily moved from an inside position to a position entirely outside of the window, and spring means for facilitating the unfolding of the bed frame when it has been positioned outside of the window. 125

7. A bed structure including links attach- 130

able to a primary supporting part, a main bed frame, folding connections between said bed frame and said links whereby, when the structure is secured to a wall adjacent a window, the bed frame can be bodily moved from an inside position to a position entirely outside of the window, and means for facili-

tating the unfolding of the bed frame when it has been positioned outside of the window.

In testimony whereof I have signed my ¹⁰ name to this specification.

CLINTON W. WILLIAMS,
Now by judicial change of name Joseph Clinton Williams.
